**FRANGIBLE CLOSURE FOR PRESSURIZED
 RECEPTACLE**
 Edmond T. Rivas, 3113 Cleary Ave., Metairie, La.
 Filed July 2, 1962, Ser. No. 207,125
 9 Claims. (Cl. 220—27)

This invention relates in general to pressurized receptacles and in particular to a frangible closure for the open end of a pressurized receptacle together with an upstanding lip on the closure member to facilitate drinking directly from the receptacle.

Pressurized receptacles for carbonated beverages and the like, as presently used, require puncturing by some form of opening device which must be kept readily available for use. Furthermore, it is not easy to drink the contents of receptacles after puncturing one end inasmuch as there is no drinking lip on the receptacle.

Therefore, it is one object of my invention to provide a receptacle having a frangible closure comprising an apertured closure member received by an open end of the receptacle, a second apertured closure member in juxtaposition to the first mentioned closure member, and a rupturable diaphragm between the closure members, the apertured closure members being normally in nonregistering relation, the second mentioned closure member being rotatable to aperture registering position at which time the pressure within the receptacle will force the rupturable diaphragm outwardly in the registering apertures, diaphragm rupturing means being located in the apertures of the second mentioned apertured closure member and adapted to rupture the portion of the diaphragm projecting into the apertures.

Another object of my invention is to provide a drinking lip projecting from the second mentioned closure member for ease in drinking the contents of the receptacle directly therefrom.

One more object of my invention is to provide a modified form of a frangible closure in which a flanged closure member is received by an open end of a receptacle, a flanged rupturable diaphragm is placed over the closure member, and a second closure member is placed over the diaphragm, a flanged locking ring being placed over the second mentioned closure member, the diaphragm, and the first mentioned closure member, the flanges on the flanged members being contiguous and in sealed relation with the receptacle, the closure members being provided with registerable apertures, the second mentioned closure member being rotatable to bring the apertures into registration when desired for rupturing the diaphragm.

Other objects and advantages as well as the construction and manner of use of my invention will be better understood by reference to the following description in connection with the accompanying drawing in which:

FIG. 1 is an exploded view of the receptacle and the various parts which go to make up the friable closure, parts being broken away to better illustrate certain other parts.

FIG. 2 is a top plan view of the closure end of the receptacle.

FIG. 3 is an enlarged fragmentary sectional view showing the action of the diaphragm rupturing means, the apertures being in registration.

FIG. 4 is a fragmentary cross sectional view of another form of my invention with apertures in nonregistering position.

Referring now the drawing by numerals of reference, 1 designates a receptacle body of standard construction insofar as the cylindrical portion is concerned, and although generally made of a suitable metal, the receptacle and associated parts may be made of other suitable

2

materials such as plastics or the like. The body 1 is provided with opposite open ends 2 and 3, one end later being sealed in the conventional manner after the contents are placed in the can or receptacle.

The other end, 2 for example, receives a closure member 4, adapted to rest against the receptacle body edge 2'. This closure member may be provided with apertures 5, preferably oppositely disposed as shown, although the number, form and position of the apertures may vary with varying results in the use of the receptacle. It may be found preferable also, because the apertures must be formed therein, to make the closure member of aluminum or some other material which will be unaffected by oxidation due to the liquids in the receptacle.

15 A rupturable diaphragm 6 which may be of any suitable material, metallic or otherwise, is placed in juxtaposition with the closure member 4. A second closure member 7, of smaller diameter than the diaphragm 6 or closure member 4 and positioned on the diaphragm 6, is provided with apertures 8 corresponding to the apertures 5 in the first mentioned closure member 4. This second closure member 7 may also be provided with an upstanding circular flange 9 inwardly disposed from the outer periphery of the closure member 7. This flange is to facilitate drinking the contents of the receptacle directly therefrom and also serves as a hand grip for turning the closure member 7.

30 Means for rupturing the diaphragm at the apertures are provided by cutting members 10, positioned in apertures 8, the use of said rupturing means being described hereinafter.

Both closure members with the intermediate diaphragm are secured in position by a locking ring 11 provided with annular flange 12 and central opening 13 to clear the upstanding drinking flange 9. The locking ring 11 also has an offset portion 14 in which is positioned the outer peripheral portion of the closure member 7. The locking ring 11 is applied with precisely the correct pressure and the annular flange 12 is suitably secured to the receptacle body 1 to hold closure members 4 and 7 with the intermediate diaphragm 6 in sealing relation with said body 1, and permitting rotative movement of the closure member 7 with drinking flange 9 whereby apertures 8 may be brought into registration with apertures 5 at which time the pressure in the receptacle from the carbonation will force the diaphragm into the apertures 8 and in the path of the rupturing means 10, said rupturing means being adapted to cut the diaphragm away at the apertures whereby the contents of the receptacle may be poured into a glass or may be partaken of directly from the receptacle by use of the upstanding flange 9.

With the frangible closure assembly completed the closure member 7 is positioned with the apertures 5 and 8 in nonregistration and the receptacle is filled and sealed at the open end 3. Where beverages without carbonation are canned it is desirable to supply sufficient internal pressure to force the diaphragm into apertures 8 for rupturing same by rotation of the closure member 7 with its diaphragm rupturing means 10.

65 The construction thus far described provides a leak-proof, pressure tight receptacle, and after vending or dispensing can be quickly opened and its contents partaken of without the need of a special opening device or a glass to receive the contents. A slight turning motion of the closure member 7 ruptures the diaphragm 6 at the apertures 5 and 8 and the contents of the receptacle can be partaken of. Later, if all of the contents are not used, the closure member 7 may be again partially rotated and although, with the diaphragm ruptured, a perfect seal is not obtained, yet the contents of the receptacle will not be spilled as long as the receptacle is kept upright.

In a modified form of my invention shown in FIG. 4,

the receptacle body 1 is supplied with a closure member 4' having peripheral flange 4", suitable apertures 5' being provided as in the first form described. The rupturable diaphragm 6' has annular flange 6" adapted to fit over flange 4'. A closure member 7' has apertures 8', cutting member 10' positioned in the apertures, and upwardly projecting handle 7". A locking ring 11' has annular flange 12' and a central opening 13' which clears the apertures 8', a portion 14' of the locking ring 11' being offset as shown to receive the outer peripheral portion 15 of the closure member 7'.

When assembled, the closure members 4' and 7' receive the rupturable diaphragm 6' between them and are held in place by the locking member 11'. Flanges 4", 6", and 12' are, by any suitable method, forced into sealing position against the body 1 of the receptacle with sufficient pressure to permit rotative movement of the closure member 7' and yet maintain a leakproof and pressure tight seal between the members and the receptacle.

Any arrangement of apertures may be used but the arrangement shown provides for an air intake aperture and an outlet aperture permitting smooth flow of liquid from the receptacle.

From the foregoing it will be seen that I have provided a new and novel frangible closure for receptacles in which the internal pressure of a carbonated beverage will force a rupturable diaphragm into registering apertures with movement of a rotary closure member causing rupture of the diaphragm to permit the contents of the receptacle to be partaken of. I have further provided a drinking ring or lip to facilitate drinking directly from the receptacle. The need for a device to open the receptacle and a separate glass to receive the contents of the receptacle are eliminated.

The receptacle with its frangible closure is extremely simple in construction and use and may employ normal methods for filling and sealing.

Obviously, changes in form, proportion and details of construction may be resorted to without departing from the spirit of my invention and I reserve all rights to such changes as come within the scope of these specifications and the claims which follow.

What I claim as new and desire to secure by Letters Patent is:

1. A frangible closure for an open end of a pressurized receptacle, comprising
a closure member received by an open end of the receptacle,
said closure member being provided with one or more apertures,
a rupturable diaphragm in juxtaposition with the closure member,
a second closure member covering the diaphragm,
said second closure member being provided with one or more apertures adapted to register with the apertures in the first mentioned closure member,
means for moving the second closure member to aperture registering and nonregistering position,
diaphragm rupturing means forming an integral part of one of said closure members and engageable with and adapted to rupture the diaphragm at the apertures when the apertures are in registration,
and locking means securing the closure members and diaphragm in juxtaposition and in sealing engagement with the receptacle.

2. A frangible closure for an open end of a pressurized receptacle, comprising
a closure member received by an open end of the receptacle,
said closure member being provided with one or more apertures,
a rupturable diaphragm in juxtaposition with the closure member,

4
a second closure member covering the diaphragm,
said second closure member being provided with one or more apertures adapted to register with the apertures in the first mentioned closure member,

means for moving the second closure member to aperture registering and nonregistering position,
diaphragm rupturing means forming an integral part of the second mentioned closure member and engagable with and adapted to rupture the diaphragm at the apertures when the apertures are in registration,
and locking means securing the closure members and diaphragm in juxtaposition and in sealing engagement with the receptacle.

3. A frangible closure for an open end of a pressurized receptacle, comprising
a closure member received by an open end of the receptacle,

said closure member being provided with one or more apertures,
a rupturable diaphragm in juxtaposition with the closure member,

a second closure member covering the diaphragm,
said second closure member being provided with one or more apertures adapted to register with the apertures in the first mentioned closure member,

means for moving the second closure member to aperture registering and nonregistering position,
pressure in the container distorting the diaphragm outwardly at the apertures when the apertures are in registration,

diaphragm rupturing means forming an integral part of one of said closure members and engageable with and adapted to rupture the diaphragm at its distorted portion in the apertures,

and locking means securing the closure members and diaphragm in juxtaposition and in sealing engagement with the receptacle.

4. A frangible closure for an open end of a pressurized receptacle, comprising
a closure member received by an open end of the receptacle,

said closure member being provided with one or more apertures,
a rupturable diaphragm in juxtaposition with the closure member,

a second closure member covering the diaphragm,
said second closure member being provided with one or more apertures adapted to register with the apertures in the first mentioned closure member,

means for moving the second closure member to aperture registering and nonregistering position,
said diaphragm expanding under pressure into said apertures when the apertures are in registration,

diaphragm rupturing means forming an integral part of the second mentioned closure member and engagable with and adapted to rupture the expanded diaphragm at the apertures,

and locking means securing the closure members and diaphragm in juxtaposition and in sealing engagement with the receptacle, with the second closure member in rotatable relation to the receptacle.

5. The structure as specified in claim 1,
and an upstanding annular member on the second closure member forming a drinking lip or flange.

6. The structure as specified in claim 1,
said locking means having a central aperture clearing the apertures in the second mentioned closure member,

depending annular flanges on the locking means,
diaphragm, and first mentioned closure member,
said flanges overlapping adjacent flanges and

the receptacle and in sealing engagement with each other.

7. A frangible closure for an open end of a pressurized receptacle, comprising
a pair of closure members received by an open end 5
of the receptacle,
registerable apertures in the closure members for
passage of fluids therethrough,
means for rotating one of the closure members
to bring the apertures into and out of registration, 10
a rupturable diaphragm between the two closure members,
said diaphragm being expandable into the registering openings by pressure within the receptacle,
and diaphragm rupturing means forming an integral 15
part of one of the closure members operable by rotation of the rotatable closure member and to rupture said diaphragm when the apertures are in registration and the diaphragm is expanded therein,
and means securing the closure members and diaphragm 20

in juxtaposition and in sealing engagement with the receptacle.

8. The structure as specified in claim 7,
and a peripheral flange carried by a closure member
and extending outwardly therefrom to form a drinking lip for the receptacle.
9. The structure as specified in claim 7,
one of said closure members abutting an open end
of the receptacle,
peripheral depending flanges on the last mentioned 15
closure member, on the diaphragm, and on the securing
means,
said peripheral flanges overlapping each other and
in sealing engagement with the receptacle.
